UNITED STATES PATENT OFFICE.

GEORGE E. HERRMANN, OF MORRISTOWN, AND BENJAMIN W. TUCKER, OF SOUTH ORANGE, NEW JERSEY.

BARREL.

1,216,805.

Specification of Letters Patent.

Patented Feb. 20, 1917.

Application filed February 16, 1912. Serial No. 677,899.

To all whom it may concern:

Be it known that we, GEORGE E. HERRMANN and BENJAMIN W. TUCKER, citizens of the United States, and residents of Morristown, county of Morris, State of New Jersey, and South Orange, county of Essex, and State of New Jersey, respectively, have invented certain new and useful Improvements in Barrels, of which the following is

10 a full, clear, and exact description.

This invention relates more particularly to barrels or other containers made of sheet steel.

The primary object of the invention is to provide a barrel or other container comprising a plurality of staves or members each of which has angular flanges along its longitudinal edges, the said flanges having parts thereof pressed or forced in opposite directions to provide oppositely arranged projecting parts, and the projecting parts of one flange being adapted to enter the grooves formed by the projecting parts of the flange of the member adjacent thereto, thus serving 25 to bind the staves or members against lengthwise relative movement and at the same time providing an effective and strong joint for the members when the barrel or container is assembled.

30 Another object of the invention is to provide simple and efficient means whereby a head may be securely held at either or both ends of the container body.

A further object of the invention is to provide simple means whereby either or both heads of the barrel or container may be interlocked with the staves or members.

A still further object of the invention is to provide a barrel or other container in 40 which the staves may be detachably held in order that an injured stave may be replaced by another or for any other purpose, and which barrel or container is so constructed that it may be readily made and assembled 45 and at the same time be inexpensive to manufacture.

With these and other objects in view, the invention will be hereinafter more particularly described with reference to the ac-

companying drawings, which form a part 50 of this specification, and will then be pointed out in the claim at the end of the description.

In the drawings, Figure 1 is a side elevation, partly broken away and partly in section, of one form of barrel or container embodying our invention.

Fig. 2 is a plan view, partly broken away and partly in section.

Fig. 3 is a detail perspective view of one 60 of the staves or members.

Fig. 4 is an enlarged fragmentary section of a part of the barrel showing one means for locking the barrel and staves together and for strengthening the ends of the barrel. 65

Fig. 5 is a sectional plan showing two of the staves assembled, the section being taken on the line V—V of Fig. 3.

Fig. 6 is a similar view to Fig. 5, except that the section is taken on the line VI—VI 70 of Fig. 3, and

Fig. 7 is a sectional plan view taken on the line VII—VII of Fig. 4.

While the invention is shown more particularly adapted for barrels having a bilged 75 or enlarged central portion, it will be understood that the invention, either as a whole or as to parts thereof, may be applied to other forms of containers.

The barrel body 10 has a plurality of 80 staves or members 11. These staves are curved and bilged centrally to provide a barrel which when assembled will be enlarged centrally so that the barrel when lying on its sides may be placed more readily on its end, or otherwise handled in a manner similar to that of the ordinary wooden barrel. Each stave has a body portion 12 and along one edge is provided with a flange 13 lengthwise thereof, and along the other edge 14 is a flange 14. These flanges 13 and 14 extend the greater part of the length of the stave and project inwardly from the body portion in order that the outer surface of the barrel may be substantially flush. Each flange is provided with a plurality of projecting portions 15 and a plurality of oppositely projecting portions

16. The projecting portions 16 extend inwardly over the body portion and the projecting portions 15 extend outwardly in an opposite direction, and these projecting portions are alternately arranged throughout the entire length of the flanges transversely thereof, the projecting portions 15 being spaced apart by the oppositely projecting portions 16. The staves are made of sheet metal and the projecting portions are formed by pressing or forcing parts of the flanges 13 and 14 in opposite directions, the projecting portions 16 forming grooves 17 which are adapted to receive the outwardly extending portions or projections 15 of the stave adjacent thereto. These grooves 17 form shoulders 18 at each end of the projections or portions 15 and the grooves and projections are angular being larger at the outer edge of the flanges. It will be evident that when the barrel body is assembled so that the projections 15 of one flange will enter the grooves 17 formed by the projections 16 of the next adjacent flange, the staves will be interlocked against lengthwise movement, and by reason of the corrugated effect of the flanges produced by the oppositely arranged projections, the staves or members will be materially strengthened.

30 A head 19 has its body 20 concaved slightly inwardly and said head is adapted to rest upon the shoulders formed by the ends of the flanges 12 and 13 of the barrel staves, which latter extend the greater part 35 of the length of the staves but not the entire length thereof. A head and its fastening means may be arranged at both ends of the barrel body or at only one end thereof as preferred, the other end being closed in any 40 desired way. Each head 19 is provided with an outwardly extending flange 21, the said flange being corrugated peripherally as shown best in Fig. 7. These corrugations may be formed in any suitable way and the 45 said flange may be divided to adapt the corrugations to be formed, or the said flange may have its corrugations pressed directly out of the flange portion and thereby utilizing the surplus metal. The corrugations 50 are formed by oppositely projecting parts or portions 22 and 23, these projections alternating throughout the entire circumference of the head, and each projecting portion forming a groove or recess. The 55 recess formed by the projecting portion 23 is adapted to receive the parts 24 of the ends 25 of the staves and located between the parts 24 is a projecting portion 26. The projecting portion 26 of each stave end 60 forms a recess to receive the projecting part 22 of the barrel head, the said projecting part 26 being angularly disposed to correspond to the angular arrangement of the projections 22 and 23 of the flange 21 of the head 19, thus holding the staves 65 against sidewise movement relative to the barrel heads and serving further to interlock with the heads and to strengthen the ends of the barrel. The ends of the barrel staves are offset to provide grooves 27 which 70 when the barrel is assembled forms a substantially continuous groove or croze for the outer edge of each of the barrel heads. The staves at the offset portion form a shoulder 28 and fitting against the shoulder 75 28 is the offset part 29 of a split compression band or member 30. This band or member 30 has a skirt portion 31 which extends for a short distance lengthwise of the barrel staves. The band has a flange 32 and 80 a second flange 33 substantially parallel thereto which are joined together by a horizontally arranged portion 34. The flanges 32 and 33 and part 34 form substantially U-shaped annular channels to receive the 85 ends of the staves or members and the flanges 21 of the barrel heads which are confined between said flanges 32 and 33. A wire or other band 35 is located under the shoulder 28 of the split ring or member 90 30 so that when the ends of the wire are twisted or otherwise held together, the band 30 may be compressed and thereby rigidly hold the stave or member and the heads together, and at the same time 95 strengthen the barrel at its ends.

Each stave or member may be depressed transversely to form grooves, as at 36 and 37, intermediate the ends thereof to form two substantially continuous grooves when 100 the staves or members are assembled. A wire or other fastening means 38 is located in the groove formed by the depressed portions 36, and a second wire or band 39 is located in a groove formed by the depressions 37. These wires 38 and 39 when the ends are twisted or otherwise tightened, will bind the body of the barrel together intermediate the ends thereof.

From the foregoing, it will be seen that a 110 simple and efficient joint is provided for barrels or other containers; that said joint provides means whereby the inwardly projecting flanges of adjacent staves may be made to interlock with each other to hold 115 the same against lengthwise movement; that said joint serves to strengthen the barrel and to form substantially continuous flanges which are adapted in themselves to support the barrel heads; that simple and efficient 120 interlocking connections are provided between the ends of the barrel staves and the barrel heads; that effective means is provided for locking the barrel staves or members and heads together and for strengthening 125 the ends of the barrels; and that said

barrel or container is inexpensive to manufacture and may be readily made and assembled.

Having thus described our invention, we claim as new and desire to secure by Letters Patent:—

A barrel or other container, comprising a plurality of members provided with unbroken flanges having alternately arranged and spaced projecting and grooved interlocking portions extending transversely of

the flanges, said projecting and grooved portions being larger at the outer edge of the flanges than at the other.

This specification signed and witnessed 15 this 13th day of February, A. D. 1912.
